(57) **CLAIM**

We claim the ornamental design for a toothbrush, as shown and described.

DESCRIPTION

FIG. 1 is a perspective front view of the toothbrush showing our new design;

FIG. 2 is a front view of the toothbrush;

FIG. 3 is a rear view of the toothbrush;

FIG. 4 is a left side view of the toothbrush;

FIG. 5 is a right side view of the toothbrush;

FIG. 6 is a top view of the toothbrush; and,

FIG. 7 is a bottom view of the toothbrush.

The broken lines shown are included for the purpose of illustrating portions of the toothbrush that form no part of the claim.
